UNITED STATES PATENT OFFICE

RALPH S. KELSO, OF ROCKFORD, ILLINOIS, ASSIGNOR TO THE FREE SEWING MACHINE COMPANY, OF ROCKFORD, ILLINOIS, A CORPORATION OF ILLINOIS

DRIVE GEAR FOR SEWING MACHINES

Application filed November 29, 1929. Serial No. 410,562.

This invention relates to sewing machines, and more particularly to novel motor driving means for a sewing machine.

It is the common practice to provide sewing machines with drive motors pivotally connected to the heads of the machines and having resilient driving pulleys carried by the armature shafts thereof and frictionally engaging the hand wheel of the machine.

Such constructions involve several disadvantages. For example, rather large and cumbersome hand wheels are employed, and since such wheels have curved outer surfaces, they soon cause the rubber or other resilient driving pulleys of the motor to become deformed.

An important object of the present invention is to provide a novel form of drive means for sewing machines wherein a resilient driving pulley is employed, but wherein the deforming of the pulley is prevented over long periods of operation.

A further object is to provide a device of the character referred to wherein the resilient driving pulley constitutes an intermediate driving element between the motor shaft and hand wheel thus permitting the latter to be made much smaller and lighter than is the common practice.

A further object is to provide novel means for encasing the driving elements of the machine and for connecting the casing elements to the machine.

A further object is to provide novel lubricating means for the shaft of the resilient driving wheel.

A further object is to provide a single fastening element for connecting the two sections of the transmission casing to each other and to the machine, and for supporting the resilient driving wheel.

Other objects and advantages of the invention will become apparent during the course of the following description.

In the drawings I have shown one embodiment of the invention. In this showing,

Figure 1 is a rear elevation of the sewing machine showing the invention applied,

Figure 2 is an end elevation of the same,

Figure 3 is a section on line 3—3 of Figure 1, parts being shown in elevation,

Figure 4 is an enlarged fragmentary end elevation of the machine, parts being shown in section,

Figure 5 is a detail perspective view of the resilient driving element and associated parts, and,

Figure 6 is a detail section on line 6—6 of Figure 2.

Referring to the drawings the numeral 10 designates a sewing machine as a whole including a bed 11, and a head including a standard 12 and horizontal arm 13. The sewing machine, aside from the driving means to be described, operates in the usual manner and forms no part of the present invention. As shown in Figures 1, 2 and 4, the operating shaft 14 extending through the arm 13 is provided at one end with a hand wheel 15 of substantially smaller diameter than ordinary constructions.

A motor 16 is arranged at the rear of the head of the machine and includes a pair of casing sections 17 secured together in any suitable manner. The motor casing is provided inwardly of the center thereof with an annular flange 18 engaging against the rear face of the head of the machine, and the latter is provided with a spherical opening 19 forming a socket to receive the inner portion 20 of the motor casing. A spring clip 21 is carried by the inner face of the motor casing and has its ends engaging the inner face of the rear wall of the head to retain the motor in operative position. It will be apparent that the motor is pivoted to swing about the horizontal axis of the spherical opening 19.

The motor is provided with an armature shaft 22 to the outer end of which is secured a preferably metallic driving wheel or disk 23. As will become apparent, it is desirable to have the disk 23 normally urged upwardly, and for this reason, a spring 24 is connected at its upper end to the motor casing, within the head of the machine, to normally effect turning movement of the motor to swing the disk 23 upwardly. A screw 25 is connected to the lower end of the spring and is adapted to adjust the tension thereof, as will be apparent,

A resilient driving wheel 26 is interposed between the disk 23 and the hand wheel 15, as clearly shown in Figure 4, and it will be apparent that the axis of the wheel 26 is below a line drawn between the axes of the wheels 15 and 23. As will become apparent, this construction assures firm engagement between the wheel 26 and the peripheries of the wheels 15 and 23 to form an efficient driving connection.

The wheel 26 is provided with a concentric central bushing 27 preferably formed of bronze or other bearing metal, and is rotatable upon a shaft 28, as shown in Figure 6. The shaft 28 is hollow as indicated at 29, and radial openings 30 communicate between the opening 29 and the interior of the sleeve 27. A wick 31 has one end extending into the opening 29 to supply lubricant to this opening and thus to the interior of the bushing 27 through the openings 30. One end of the shaft 28 is enlarged as at 32 to form a collar adapted to retain the bushing 27 on the shaft, while the opposite end of this shaft is reduced and riveted or otherwise secured as at 33 to one end of an arm 34. The opposite end of the arm 34 is provided with a sleeve 35 arranged parallel to the axis of the shaft 28 and having an opening therethrough for a purpose to be described.

The wheels 23 and 26 constitute the transmission elements of the device, and these elements are covered by a casing indicated as a whole by the numeral 36. This casing is formed in two sections 37 and 38, the former of which is provided with a wall 39 surrounding the transmission elements and contacting the casing member 38. As shown in Figures 1 and 6, the casing member 38 is formed as a flat plate and is provided on its inner face with a laterally projecting boss 40 having an opening therethrough.

As shown in Figure 1, the inner end of the boss 40 seats against the inner wall of a recess 41 formed in the outer motor casing section 17. These casing sections are provided with aligned openings 42, and the inner opening 42 is internally threaded to receive the inner threaded end of a screw 43. This screw is provided with a head 44 countersunk in the outer casing section 37, and the screw projects through the boss 40, as shown in Figure 1. It will be apparent that the screw 43 serves to connect the two casing sections 37 and 38 to each other and to the motor 16. Referring to Figure 4, it will be noted that the portion of the screw 43 lying within the casing 36 passes through the sleeve 35, and accordingly pivotally supports the arm 34. Since the casing 36 is carried by the motor 16, it obviously moves therewith about the axis of the spherical opening 19.

Referring to Figure 6, the numeral 45 des-

ignates an integral boss carried by the outer face of the casing section 37 and provided with an opening therethrough receiving a wick 46 extending within the transmission casing and contacting with the outer end of the wick 31.

The operation of the device is as follows:

It will be apparent that the spring 24 operates to swing the motor about the axis of the spherical opening 19, and thus the driving disk 23 of the motor shaft will be constantly urged upwardly. This action maintains the disk 23 in snug contact with the resilient driving member 26, and also retains the latter element in firm engagement with the periphery of the hand wheel 15. The wheel 26 is carried by the pivoted arm 34, and accordingly the wheel 26 is adapted to alter its position whereby it firmly engages the wheels 15 and 23 with uniform pressure. The arrangement of the axis of the wheel 26 below a line joining the axes of the wheels 15 and 23 operates in such a manner that the tendency of the wheel 23 to move upwardly under the influence of the spring 24 urges the wheel 26 more tightly into engagement with the wheels 15 and 23, thus increasing the efficiency of the driving connection.

In standard sewing machine driving constructions, it is the common practice to place a resilient driving wheel directly on the motor shaft to contact with and drive the hand wheel of the machine. Obviously such arrangement requires the use of a relatively heavy and cumbersome driving wheel 15 whereas in the present construction the use of an intermediate resilient driving wheel between the motor shaft and the hand wheel permits the use of a hand wheel of materially lighter construction and smaller diameter.

The hand wheels of all sewing machines are formed with convex peripheries and with the standard constructions, the curved outer periphery of the hand wheel constantly contacts with the resilient driving wheel on the motor shaft with the result that such driving wheel becomes deformed and tends to lose its driving efficiency. With the present construction, the curved periphery of the hand wheel tends to depress the peripheral portion of the wheel 26 to deform the resilient material of which this wheel is formed, but this tendency is overcome by virtue of the fact that the wheel bears under uniform pressure against the wheels 15 and 23, and the outer face of the latter wheel is transversely flat thus preventing the deforming of the wheel 26. Thus the traction between the friction driving elements remains constant and efficient over long periods of time.

The resilient driving wheel is properly lubricated merely by occasionally oiling the upper end of the wick 46. The lubricant will be carried by capillary attraction downwardly through the wick 46 to the wick 31, from

which it is delivered in small quantities to the interior of the bushing 27 through the openings 29 and 30. Thus it will be apparent that proper lubrication readily may be provided 5 for the resilient driving wheel, while the shafts 14 and 22 can be lubricated by the usual means provided for such purpose.

It is to be understood that the form of the invention herewith shown and described is 10 to be taken as a preferred example of the same and that various changes in the shape, size and arrangement of parts may be resorted to without departing from the spirit of the invention or the scope of the sub- 15 joined claims.

I claim:

1. The combination with a sewing machine including a rotatable element having a transversely curved peripheral surface, of a motor having a drive shaft, a cylindrical driving member mounted on said shaft, a substantially cylindrical resilient frictional driving connection arranged between and contacting with said driving member and said rotatable 25 element, and resilient means normally urging said driving member toward said driving connection and said rotatable element.

2. The combination with a sewing machine including a rotatable element, of a motor having a drive shaft, a driving member mounted on said shaft, means for pivotally connecting said motor to a stationary portion of the sewing machine whereby said driving member is adapted to swing toward and away from said 35 rotatable element, spring means tending to revolve said motor whereby said driving member is urged toward said rotatable element, a resilient frictional driving connection arranged between and contacting with said 40 driving member and said rotatable element, an arm pivotally supported at one end by the motor, and a shaft carried by the free end of said arm and rotatably supporting said driving connection.

3. The combination with a sewing machine including a rotatable element having a transversely curved peripheral surface, of a motor having a drive shaft, a cylindrical driving member mounted on said shaft, a substantially 50 cylindrical resilient frictional driving connection arranged between and contacting with said driving member and said rotatable element, means for pivotally connecting said motor to a stationary portion of a sewing ma-

chine whereby said driving member is adapted to swing toward and away from said rotatable element, spring means tending to urge said driving member toward said driving connection and said rotatable element, and floating means for rotatably supporting said driving connection to permit it to automatically engage under uniform pressures against said driving member and said rotatable element.

4. The combination with a sewing machine

including a rotatable element, of a motor having a drive shaft, a driving member mounted on said shaft, means for pivotally connecting said motor to a stationary portion of the sewing machine whereby said driving member is adapted to swing toward and away from said rotatable element, spring means tending to revolve said motor whereby said driving member is urged toward said rotatable element, a resilient frictional driving connection arranged between and contacting with said driving member and said rotatable element, said driving connection being arranged to one side of the plane passing through the axes of said driving member and said rotatable element, a pivot pin carried by said motor, an arm pivotally supported at one end by said pivot pin, and a shaft carried by the free end of said arm and rotatably supporting said driving connection.

5. The combination with a sewing machine including a rotatable element, of a motor including a casing and a drive shaft, a driving member mounted on said shaft, a resilient frictional driving connection arranged between and contacting with said driving member and said rotatable element, a casing surrounding said driving member and said driving connection and including a pair of sections, an arm having means at one end thereof for rotatably supporting said driving connection, and common means for securing said casing sections to each other and to the casing of the motor and for pivotally supporting the other end of said arm.

6. A device of the character described comprising a motor including a casing and a drive shaft, a driving member carried by said shaft, a resilient frictional driving connection engaging said driving member, means for supporting said motor with respect to a sewing machine whereby said driving connection will have frictional engagement with the hand wheel of the machine, and floating means carried by said casing for rotatably supporting said driving connection to permit it to automatically engage under uniform pressures against said driving member and the hand wheel of the machine.

7. A device of the character described comprising a motor including a casing and a drive shaft, a driving member carried by said shaft, a resilient frictional driving connection engaged by said driving member, means for supporting said motor with respect to a sewing machine whereby said driving connection will have frictional engagement with the hand wheel of the machine, an arm pivotally supported at one end by the casing of said motor, and means connected at the free end of said arm for rotatably supporting said driving connection.

8. A device of the character described comprising a motor including a casing and a drive shaft, a driving member carried by said

- shaft, a resilient frictional driving connection engaged by said driving member, means for supporting said motor with respect to a sewing machine whereby said driving connection will have frictional engagement with the hand wheel of the machine, an arm having means at one end for rotatably supporting said driving connection, a casing for said driving member and said driving connection and including a pair of sections, and common means for securing said casing sections to each other and to the casing of the motor and for pivotally supporting the other end of said arm.
- 13 9. A device of the character described comprising a motor including a casing and a drive shaft, a driving member carried by said shaft, a frictional driving connection engaging said member, means for supporting said motor with respect to a sewing machine whereby said driving connection will have frictional engagement with the hand wheel of the machine, a casing covering said driving member and said driving connection, and common means for securing said second named casing to said motor casing and for supporting said driving connection for floating movement to permit it to automatically engage under uniform pressures against said driving member and the hand wheel of the machine.
- 13 10. A device of the character described comprising a motor including a casing and a drive shaft, a driving member carried by said shaft, a frictional driving connection engaging said member, means for supporting said motor with respect to a sewing machine whereby said driving connection will have frictional engagement with the hand wheel of the machine, a casing covering said driving member and said driving connection, an arm having means including a shaft arranged at one end thereof for rotatably supporting said driving connection, said last named shaft having an axial opening extending thereto from one end and being further provided with radial openings communicating with said axial opening, capillary means arranged in the openings of said last named shaft, means carried by said casing for supplying lubricant to said capillary means, and common means for securing said second named casing to the casing of said motor and for rotatably supporting the other end of said arm.

In testimony whereof I affix my signature.
RALPH S. KELSO.
